REFRIGERATION

Nils Widell, Stockholm, Sweden, assignor, by
mesne assignments, to Servel, Inc., New York,
N. Y., a corporation of Delaware

Application March 14, 1938, Serial No. 195,715
In Germany March 16, 1937

23 Claims. (Cl. 62—119.5)

This invention relates to refrigeration, and more particularly to control of refrigeration systems.

It is an object of the invention to provide an improvement for controlling refrigeration systems, particularly systems of the kind containing an auxiliary agent or inert gas into which refrigerant evaporates.

This is accomplished by flowing liquid refrigerant to a place of accumulation and conducting liquid therefrom to a place of evaporation, and removing liquid from the place of accumulation to effect temperature control of the place of evaporation and also to cause abnormal rise of temperature to melt any frost or ice formed at the place of evaporation. In a refrigeration system of the kind containing an inert gas, refrigerant fluid may be removed from the place of accumulation by heating and diverted to the gas circuit whereby the flow of gas therein may be reduced or stopped.

The heating of liquid refrigerant at the place of accumulation may be controlled automatically to normally maintain the place of evaporation at a desired low temperature or temperature range. Such normal control may be modified at will to effect defrosting or to increase the refrigerating effect produced at the place of evaporation, as when quick freezing is desired.

The liquid at the place of accumulation may be heated directly or by indirect heat transfer. The heat from a part of the refrigeration system may be utilized to effect indirect heating with the aid of a heat transfer circuit.

The invention, together with the above and other objects and advantages thereof, will be more fully understood upon reference to the following description and the accompanying drawings forming a part of this specification, and of which:

Fig. 1 illustrates more or less diagrammatically a refrigeration system embodying the invention;

Fig. 2 is an enlarged sectional view taken on line 2—2 of Fig. 1 to illustrate parts of the control more clearly;

Fig. 3 is an enlarged fragmentary sectional view taken on line 3—3 of Fig. 2; and

Fig. 4 illustrates more or less diagrammatically a modification of the invention.

In Fig. 1 the invention is shown embodied in an absorption refrigeration system of a uniform pressure type containing a pressure equalizing gas or auxiliary agent. A system of this type includes a generator 10 containing a refrigerant in solution in a body of absorption liquid. Although I do not wish to be limited thereto, the refrigerant

and absorption liquid may be ammonia and water, respectively. The generator 10 is heated in any suitable manner, as by a burner 11, for example, which projects its flame into the lower end of a flue 12. By heating generator 10, refrigerant vapor is expelled out of solution and flows upward through an air-cooled rectifier 13 and thence into a condenser section 14a of an air-cooled condenser 14.

Refrigerant liquefied in condenser section 14a flows into a liquid trap formed by a conduit 15. When sufficient liquid accumulates in trap 15, liquid flows through conduit 16 into an upper cooling element 17 and thence through a conduit 18 into a lower cooling element 19. The cooling elements 17 and 19 are arranged in a thermally insulated space 20.

Liquid refrigerant in lower cooling element 19 evaporates and diffuses into an inert gas, such as hydrogen, for example, thereby producing a refrigerating effect. The inert gas enters lower cooling element 19 through a conduit 21. The resulting rich gas mixture of refrigerant and inert gas flows from cooling element 19 through a vessel 22 into an outer passage 23 of a gas heat exchanger 24.

The upper cooling element 17 is connected by conduits 25 and 26 to the outer passage 23 of the gas heat exchanger. Liquid refrigerant in upper cooling element 17 evaporates and diffuses into rich gas which circulates therethrough, thereby producing a refrigerating effect and precooling liquid flowing to the lower cooling element 19.

Refrigerant vapor not liquefied in condenser section 14a flows from the left-hand leg of trap 15 into a second condenser section 14b. Refrigerant liquefied in condenser section 14b flows through conduits 27, 28, and 18 into the lower cooling element 19.

From the outer passage 23 of gas heat exchanger 24 the rich gas mixture flows through a vertical conduit 29 into the lower end of an air-cooled absorber 30. The absorber 30 is diagrammatically shown in the form of a looped coil having a plurality of cooling fins fixed thereto.

In absorber 30 refrigerant vapor is absorbed by absorption liquid which enters the upper part thereof through a conduit 31. The hydrogen or inert gas, which is practically insoluble and weak in refrigerant, is returned to the upper part of lower cooling element 19 through a conduit 32, a plurality of tubes 33 forming an inner passage of the gas heat exchanger, and conduit 21. The enriched absorption liquid flows from absorber 30 into an accumulation vessel 34.

From vessel 34 enriched liquid flows through a conduit 35 and an inner passage of liquid heat exchanger 36 to a coil 37 which is disposed about the lower end of flue 12. Liquid is raised by vapor-lift action from coil 37 through conduit 38 into the upper part of generator 10. Absorption liquid weak in refrigerant flows from the lower part of generator 10 through conduit 39, the outer passage of liquid heat exchanger 36 and conduit 38 into the upper part of absorber 30.

The lower end of condenser section 14b is connected by vertical conduit 27, vessel 40, and conduit 41 to the gas circuit, as at the gas heat exchanger 24, for example, so that any inert gas which may pass into the condenser can flow into the gas circuit. Refrigerant vapor not liquefied in condenser 14 flows through conduit 27 to displace inert gas in vessel 40 and force such inert gas through conduit 41 into the gas circuit. By forcing gas into the gas circuit in this manner, the total pressure in the system is raised, whereby an adequate condensing pressure is obtained to insure condensation of refrigerant vapor in the condenser.

Since gas weak in refrigerant enters lower cooling element 19 through conduit 21 and rich gas flows through upper cooling element 17, the gas in the upper cooling element 17 contains a greater amount of refrigerant vapor than the gas in lower cooling element 19. The partial vapor pressure of refrigerant vapor is therefore higher in cooling element 17 than in cooling element 19, and evaporation of liquid takes place at a higher temperature in cooling element 17 than in cooling element 19.

The upper cooling element 19 may be primarily employed for cooling space 20 and is provided with a plurality of heat transfer fins 42 to increase the effective heat transfer surface. The lower element 19 is preferably provided with a limited heat transfer surface, and, since evaporation of liquid takes place at a lower temperature therein, it may be employed as a freezing unit.

In accordance with this invention, in order to control the operation of the refrigeration system just described, a heat transfer circuit is provided for heating liquid refrigerant in trap 15. Although heating of liquid in trap 15 may be effected by any suitable source of heat, it is preferred to utilize heat from a part of the refrigeration system to heat trap 15.

The heat transfer circuit for transferring heat to trap 15 from a part, such as generator 10, for example, includes an evaporation member 43. The evaporation member 43 is arranged in good heat exchange relation with generator 10 and is preferably embedded in insulation 44. The upper end of evaporation member 43 is connected by a conduit 45 to an upper part of a condenser member 46 which is in the form of a jacket disposed about the right-hand leg of trap 15. The lower part of member 46 is connected to a vertical conduit 47 which is connected at its lower end to an accumulation vessel 48. The lower part of vessel 48 is connected by conduit 49 to the lower part of evaporation member 43. A control device 50, which will be described hereinafter, is connected to the lower end of conduit 49.

The evaporation member 43, condenser 46, vessel 48, and connecting conduits form a hermetically sealed circuit which is partly filled with a suitable volatile liquid. The control device 50 controls the flow of liquid from vessel 48 and conduit 49 to evaporation member 43. When

the refrigeration system is in operation and generator 10 is being heated, liquid in evaporation member 43 is heated and evaporated. The vapors pass upwardly through conduit 45 into condenser member 46. The vapor is condensed in member 46 and flows downward through conduit 47, vessel 48, and conduit 49 into the lower part of evaporation member 43 where it is again evaporated. The volatile fluid circulates naturally in the manner just described and serves as a heat transfer agent. The evaporation of liquid in member 43 takes up heat from generator 10, and the condensation of the vapors in jacket or member 46 gives up heat to liquid in trap 15.

As will be seen in Fig. 1, the right hand leg 15 of trap 15 is connected by a conduit 51 to conduit 32 through which gas weak in refrigerant flows from absorber 30 to lower cooling element 19. When liquid refrigerant is heated in trap 15, therefore, the refrigerant vapor produced by such heating as well as liquid refrigerant can flow into the gas circuit.

The control device 50 for controlling the heat transfer circuit includes a casing 52 having bosses 53 and 53' which form inlet and outlet openings, respectively, for the volatile liquid. As shown in Fig. 2, liquid flows from the inlet opening at boss 53 past a valve 54 and thence to the outlet opening at boss 53'. The valve is provided with a stem 55 which extends through an opening in casing 52 and is secured at its outer end to a plate 56. To raised shoulders formed on plate 56 and casing 52 are secured the opposite ends of an expandible and contractible bellows 57, whereby the volatile fluid circuit is effectively sealed. The valve 54 is urged to its closed position by a coil spring 58 which is disposed between the end of casing 52 and a flange at the periphery of plate 56.

The opposite end of control device 50 includes a casing 59 having an annular member 60 secured to the inner end thereof. To the annular member 60 is secured one end of a bellows 61 which in turn is secured at its other end to a plate 62. Between the annular member 60 and plate 62 is disposed a coil spring 63 tending to expand the bellows 61. The plate 62 is formed with a hollow cylindrical portion which extends toward the annular member 60. To the outer end of the cylindrical portion is threadedly secured a stud or cap screw 64.

The casings 52 and 59 are secured to the opposite ends of a cylindrical sleeve 65 having diametrically opposite openings 66. A shaft 67 having a handle 68 extends through the openings 66 in sleeve 65. To shaft 67 is fixed a cylindrical member 69 having a cam 70 of the shape shown in Fig. 3.

When handle 68 is turned so that cam 70 is in the position shown in Fig. 3, movements of bellows 61 will be transmitted through the cam to plate 56, whereby automatic control of valve 54 is effected, as will be described hereinafter. When cam 70 is moved so that the radius Y is moved to the line X-X, no movements of bellows 61 will be transmitted to plate 56 and valve 54 will remain closed all of the time by action of spring 58. When cam member 69 is turned so that the radius Z is moved to the line X-X, valve 54 will open and remain open independent of any movements of bellows 61.

To the closed end of casing 59 is connected one end of a conduit 71 which is connected at its other end to a thermal bulb 72. The thermal bulb 72 is arranged in good thermal contact with vessel 22 which may be considered a part of lower cooling 75

- element 19. The bulb 72, conduit 71, and space 73 defined by casing 59 and bellows 61 constitute an expansible thermostat which may be filled with water or other suitable freezing solution. 5
When the solution freezes due to a decrease in temperature of cooling element 19, the expansion of the frozen solution causes contraction of bellows 61. Conversely, when the frozen solution melts due to an increase in temperature of cooling element 19, the solution contracts and bellows 61 expands by action of spring 63.

During normal operation, the refrigerant fluid, inert gas, and absorption liquid circulate in the refrigeration system in the manner described 15 above whereby cooling elements 17 and 19 produce a refrigerating effect. With normal operation, hydrogen or inert gas circulates continuously in the gas circuit including the cooling element 19 and absorber 30. This circulation of hydrogen 20 or inert gas is due to the difference in specific weight of the rich mixture of inert gas and vaporous refrigerant in cooling element 19, outer passage 23 of gas heat exchanger 24, and vertical conduit 29; and the weak mixture of these gases 25 in absorber 30, conduit 32, inner passage 33 of the gas heat exchanger, and conduit 21. Due to the difference in specific weight of the columns of rich and weak gas, therefore, a force is developed in the gas circuit for causing flow of rich 30 gas toward absorber 30 and flow of weak gas toward cooling element 19. Similarly, due to the difference in specific weight of rich gas in conduit 25 and richer gas in cooling element 17 and conduit 26, a force is developed for causing flow 35 of gas in the local circuit including upper cooling element 19.

The above normal operation of the refrigeration system takes place when valve 54 of control device 50 is closed and no heat is transferred 40 from generator 10 to trap 15 by the closed heat transfer circuit. When valve 54 is opened, however, volatile liquid is permitted to flow from vessel 48 and conduit 49 to evaporation member 43, whereby heat is transferred from generator 10 to jacket 46, as explained above, to cause heating and evaporation of liquid in trap 15. Liquid in the right-hand leg of trap 15 is raised by vapor-lift action due to the vapor bubbles formed therein, whereby the raised liquid overflows through conduit 51 into conduit 32. With liquid flowing from trap 15 through conduit 51, the liquid level in trap 15 is lowered. Under these conditions refrigerant vapor liquefied in condenser section 14a flows into the trap, 55 and, since the liquid level therein is lowered, no flow of liquid into cooling elements 17 and 19 through conduit 16 will take place.

If desired, all of the liquid in trap 15 may be removed to bring about a reduction in the production of cold by space cooling element 17. It usually is not necessary to remove all of the liquid from trap 15, however, and this is particularly true in a refrigeration system containing 60 an auxiliary medium or inert gas. Sufficient heating of trap 15 is effected where the amount of liquid overflowing through conduit 51 into conduit 32 is effective to reduce or stop the circulation of gas in the gas circuit. The liquid flowing into conduit 32 from trap 15 evaporates and diffuses into weak gas flowing from absorber 30 to lower cooling element 19. This increases the specific weight of the column of weak gas in the gas circuit and reduces the difference in specific weight of the columns of rich and weak gas, whereby the force normally de-

veloped for circulation of gas in the gas circuit is reduced. When the flow of weak gas into cooling element 19 is reduced or stopped, evaporation of refrigerant takes place at a higher temperature or no evaporation may take place 5 due to the higher partial pressure of refrigerant vapor. With no flow of liquid into upper cooling element 17 and the circulation of gas in the gas circuit reduced or stopped, therefore, less cold is produced by cooling elements 17 and 10 19 and the temperatures of these cooling elements rise.

With the improved control of the character described, the refrigeration system may be controlled independently of the energy supplied to 15 the refrigeration system. This is particularly desirable in cases where the energy supply is controlled only with difficulty, as with oil burners or the waste heat of heating plants which supply heat indirectly to the refrigeration system 20 with the aid of an indirect heat transfer circuit. Even in cases where the energy supplied to the refrigeration system may be readily controlled, the provision of a heat transfer circuit of the character shown is desirable inasmuch as control of the refrigeration system may be effected 25 without the necessity of reducing or shutting off the energy supply. This is particularly advantageous in that the production of cold may be immediately instigated when normal operation is resumed after a modified period of operation during which the production of cold is reduced.

The control device 50 may be adjusted to maintain storage space 20 substantially at a constant 35 temperature or temperature range or to effect defrosting. When storage space 20 is to be maintained at a desired low temperature or temperature range, handle 68 is turned so that cam 70 is in the position shown in Fig. 3. With cam 40 member 70 in this position, movements of bellows 61 will be transmitted through the cam to valve 54. The freezing solution in the expansible thermostat will freeze and expand when cooling element 19 tends to fall below a 45 desired low temperature which is the freezing temperature of the solution. With freezing of the solution and resulting expansion thereof, contraction of bellows 61 takes place thereby causing valve 54 to open. The openings 66 in 50 sleeve 55 are elongated, as shown in Fig. 3, thereby permitting movement of cam 70 with movement of bellows 61. Due to opening of valve 54, liquid will flow into evaporation member 43 of the heat transfer circuit and heating of trap 55 15 will take place, as explained above. This will decrease the rate of flow of liquid refrigerant through conduit 16 into cooling elements 17 and 19, and also reduce the circulation of gas in the gas circuit. When this occurs, the refrigerating effect produced by cooling elements 17 and 19 will be reduced.

Conversely, when space 20 tends to rise above the desired low temperature or temperature range which is above the freezing temperature 65 of the solution in the expansible thermostat, the frozen solution will melt. With melting of the frozen solution and consequent contraction thereof, bellows 61 will expand due to the action of spring 63. This permits valve 54 to close 70 due to action of spring 58, thereby shutting off the flow of volatile liquid into evaporation member 43. Under these conditions heating of trap 15 is no longer effected and the refrigerating 75

effect produced by cooling elements 17 and 19 will be increased.

When it is desired to effect defrosting, handle 68 of control device 50 is turned so that radius 5 Z in Fig. 3 is moved to the line X—X. When this is done shaft 67 is moved to one end of the elongated openings 66 and cam 70 is effective to open valve 54. Valve 54 will remain open independent of the expansible thermostat and 10 heat will be transferred from generator 10 to trap 15. With heating of liquid in trap 15 the production of cold by cooling elements 17 and 19 will be reduced. This will permit the temperatures of cooling elements 17 and 19 to rise, 15 so that frost accumulated thereon will melt. When defrosting is completed, handle 68 may again be turned so that automatic control of the refrigeration system may be resumed in response to the temperature of lower cooling element 19.

When it is desired to modify the normal automatic control and prevent heating of trap 15 so that the refrigerating effect produced by cooling elements 17 and 19 will be at a maximum, 25 handle 68 may be turned so that radius Y will be moved to the line X—X. In this position cam 10 is ineffective to open valve 54 by itself and also ineffective to transmit movements of bellows 61 to valve 54. The valve 54 will therefore 30 remain closed all of the time and the refrigerating effect produced by cooling elements 17 and 19 will be at a maximum. The normal automatic control of the refrigeration system is modified in this manner when the maximum 35 production of cold is desired, as when quick freezing of ice and other frozen matter is necessary.

Instead of locating the heating jacket 46 about the right-hand leg of the trap 15, the heating jacket may be arranged about the trap 40 in such a manner that liquid is also raised in the left-hand leg of the trap when the latter is heated. In such case only a part of the liquid flows from trap 15 through conduit 51 when heating of the trap is effected, and the remaining liquid flows from the trap through conduit 45 16 or through both conduits 16 and 21 into the cooling elements. Since the circulation of gas in the gas circuit is reduced and may be completely stopped when such liquid enters the cooling elements, normal evaporation of liquid in the 50 cooling elements will not take place.

The lower cooling element 19 may be provided with inserts 74 so that shallow pools of liquid refrigerant may be maintained in the entire lower cooling element. In addition, the vessel 22 is connected in series relation with lower cooling element 19 so that unevaporated liquid may be accumulated therein. When heating of trap 15 is stopped and normal operation of the refrigeration 60 system is resumed, the gas circulates in the gas circuit and the liquid in vessel 22 is immediately available for the production of cold. If trays containing water to be frozen are inserted into the lower cooling element 19, for example, the load on the cooling element is temporarily increased. Due to this temporary increase in load, more liquid refrigerant can evaporate and diffuse into inert gas. By providing vessel 22 liquid refrigerant is immediately available in the 70 freezing unit to take care of the temporary increase in load.

Since generator 10 may be heated continuously with the type of control provided, the amount of liquid refrigerant that may be accumulated in vessel 22 is preferably limited so that circulation

of liquid will always take place in the liquid circuit including generator 10, liquid heat exchanger 36, and absorber 30. In other words, during operation the liquid level in generator 10 will always be above the upper end of conduit 5 31 so that liquid will flow from generator 10 to the upper part of absorber 30.

The vessel 22 is provided with baffles 75 and 76 having openings 77 and 78 in the top and bottom parts thereof, as shown in Fig. 1. At the left-hand end of vessel 22 is provided an overflow conduit 79 having its lower end connected to the lower part of the vessel and its upper end connected to conduit 80 at approximately the same height as the openings 77 in baffles 75. 15

If the vessel 22 should contain absorption solution, unevaporated liquid flowing into the right-hand pocket of vessel 22 settles upon top of the absorption solution and presses the latter into the second smaller pocket through the bottom opening 78 in the first baffle 76. This raises the level of absorption solution in the second pocket whereby absorption solution flows through the successive pockets or chambers in vessel 22 and overflows through conduit 79 into conduit 80. 20 25

When liquid refrigerant enters the second smaller pocket through the bottom opening 78 in the first baffle 76, the liquid causes a mechanical lifting of absorption solution in the second smaller pocket. This is due to the flow of liquid 30 refrigerant and the fact that the absorption solution and liquid refrigerant stratify, so that absorption solution flows into the next larger pocket. In this manner any absorption solution in vessel 22 is moved from the right to the left 35 therein and thence into conduit 80, whereby the vessel is purged of absorption solution.

In Fig. 4 is illustrated a modification of the invention. The refrigeration system in Fig. 4 is similar to that illustrated in Fig. 1 and differs 40 therefrom in that it includes only a single condenser 14 and a single cooling element 17'. The remaining parts of the system are the same as in Fig. 1 and designated by the same reference numerals. In Fig. 4 liquid refrigerant flows from 45 condenser 14 into a gas separating chamber 81 and thence through conduit 16' into the upper part of cooling element 17'. Conduit 16' is U-shaped to form a liquid trap and the lower part thereof is in heat exchange relation with the 50 outer passage of the gas heat exchanger 24.

Gas weak in refrigerant flows from the inner passage of gas heat exchanger 24 through conduit 21' into the upper part of cooling element 17'. The resulting rich gas mixture of refrigerant and inert gas flows from the lower part of the cooling element through conduit 82 into the outer passage of gas heat exchanger 24, and thence through vertical conduit 29 into the lower part 55 of absorber 30.

A vent conduit 83 is connected to the chamber 81 and to the gas circuit, as at the gas heat exchanger 24, for example. The vent conduit 83 extends upward from chamber 81 and then downwardly to the gas heat exchanger, so that any 60 gas which passes through the condenser 14 can flow into the gas circuit and not be trapped in the condenser.

The condenser member 46' of the heat transfer circuit is arranged in good heat exchange relation with conduit 16'. If desired, the condenser member 46' and the portion of conduit 16' in contact therewith may be embedded in insulation. 70

When control device 50 is operated either manually or automatically in response to the expans-

sible thermostat to permit liquid to flow from conduit 49 to evaporation member 43, heat is transferred from generator 10 to condenser member 46'. The liquid in conduit 16' is heated and evaporated, and due to the forming of vapor bubbles, liquid is raised by vapor-lift action in the right-hand part of conduit 16'. The liquid is raised through chamber 81 and vent conduit 83 into the gas circuit. In this manner refrigerant in liquid or vapor form may be caused to flow from conduit 16' to the portion of the gas circuit through which weak gas flows from absorber 30 to cooling element 17'.

The volatile liquid employed in the heat transfer circuit preferably possesses such physical properties that a low pressure will prevail in the circuit for the temperature existing therein. The circuit is preferably evacuated before it is charged with the volatile liquid. If desired, the circuit may be charged with a gas in addition to the volatile liquid so that evaporation of liquid in the evaporation member will take place at a desired temperature. Instead of employing a volatile liquid, the heat transfer circuit may be filled with a liquid which remains in a liquid state. In such case natural circulation of liquid is effected due to differences in specific gravity of the liquid in different portions of the circuit.

Although several embodiments of the invention have been shown and described, it will be apparent to those skilled in the art that various modifications and changes may be made without departing from the spirit and scope of the invention. While the improved control is particularly adapted for refrigeration systems in which energy is supplied thereto continuously, the control may also be employed in other types of refrigeration systems, as pointed out above. It is therefore contemplated to cover all modifications and changes which come within the spirit of the invention, as pointed out in the following claims.

What is claimed is:

1. In the art of refrigeration employing a system using inert gas into which liquid refrigerant evaporates at a place of evaporation, the improvement which consists in collecting liquid refrigerant at a place of accumulation and conducting liquid therefrom to the place of evaporation, and removing refrigerant fluid from the place of accumulation to a place in the system other than the place of evaporation to interfere with the evaporation of liquid refrigerant in the place of evaporation.

2. In a refrigeration system, the improvement which consists in flowing liquid refrigerant to a place of accumulation and conducting liquid therefrom to a place of evaporation when liquid is at or above a predetermined level at the place of accumulation, and flowing refrigerant from the place of accumulation to a place in the system other than the place of evaporation to lower the liquid at the place of accumulation below the predetermined level to stop the flow of refrigerant to the place of evaporation.

3. In the art of refrigeration in which evaporation of liquid refrigerant takes place in the presence of an inert gas at a place of evaporation, inert gas enriched with refrigerant vapor flows from the place of evaporation to a place of absorption, and inert gas weak in refrigerant vapor flows from the place of absorption to the place of evaporation, the flow of gas being due to the difference in specific weight of columns of inert gas enriched with refrigerant vapor and weak in

refrigerant vapor, the improvement which consists in flowing liquid refrigerant fluid into the column of gas weak in refrigerant at a place other than the place of evaporation to reduce the flow of gas between the place of evaporation and the place of absorption.

4. In a refrigeration system, the improvement which consists in flowing liquid refrigerant to a place of accumulation and conducting liquid therefrom to a place of evaporation, and heating a heat transfer fluid by a part of the system and flowing the fluid from such part in heat transfer relation with the place of accumulation to heat liquid therein and cause flow of refrigerant therefrom to a place in the system other than the place of evaporation to interfere with evaporation of liquid refrigerant in the place of evaporation.

5. An absorption refrigeration system including a cooling element and an absorber connected to form a gas circuit for circulating gas therein by a force developed by the difference in specific weight of columns of gaseous fluid, a member to conduct liquid refrigerant to said cooling element, and conduit means to conduct refrigerant from said member to a part of the gas circuit other than the cooling element to reduce the force developed in the gas circuit for circulating gas therein.

6. A refrigeration system including a heated part and a cooling element, a member to conduct liquid refrigerant to said cooling element, conduit means connecting said member and a portion of the system other than said cooling element, and a vaporization-condensation circuit containing a volatile fluid and having a vaporization portion in heat exchange relation with said heated part and a condensation portion in heat exchange relation with said member.

7. A refrigeration system as defined in claim 6 and including means for controlling the circulation of volatile fluid in said vaporization-condensation circuit.

8. A refrigeration system as defined in claim 6 and including means responsive to a temperature condition affected by said cooling element for controlling flow of volatile fluid in said vaporization-condensation circuit.

9. An absorption refrigeration system of an inert gas type comprising inter-connected parts including a gas circuit having a cooling element into which liquid refrigerant is conducted for evaporation in the presence of the inert gas to produce a refrigerating effect, such cooling element being subject to formation of frost or ice, means including a liquid trap connected in said system to cause flow of hot vaporous fluid into said gas circuit when liquid is removed from said trap, so that the temperature of said cooling element is raised sufficiently to melt frost or ice, and heat transfer structure comprising a closed fluid circuit containing a heat transfer fluid and having one part associated with a source of heat and another part associated with said trap for transferring heat from the source of heat to the trap to remove liquid from the latter by heating.

10. The combination set forth in claim 9 and including means to control transfer of heat to said trap by said heat transfer structure.

11. The combination set forth in claim 9 in which a part of the system serves as the source of heat.

12. The combination set forth in claim 9 in which the closed fluid circuit contains a volatile fluid and in which said one part constitutes a vaporization portion and said other part con-

- stitutes a condensation portion of a vaporization-condensation system.
13. An absorption refrigeration system of an inert gas type including a cooling element, a member for conducting liquid refrigerant to said cooling element for evaporation therein in the presence of inert gas to produce a refrigerating effect during normal operation of the system, such cooling element being subject to formation of frost or ice, means including a liquid trap to cause an increase in partial pressure of refrigerant vapor in said cooling element when liquid is removed from said trap, so that the temperature of said cooling element is raised sufficiently to cause melting of frost or ice, and said trap being so connected and arranged in said system that, when liquid is removed therefrom to cause an increase in partial pressure of refrigerant vapor in said cooling element, liquid is also conducted from said trap to said cooling element, said cooling element having sufficient capacity to hold liquid conducted thereto from said trap whereby such liquid is immediately available to produce a refrigerating effect when liquid is permitted to remain in said trap and normal operation of the system is resumed.
14. An absorption refrigeration system of an inert gas type comprising a plurality of parts and having a gas circuit including a cooling element subject to formation of frost or ice and into which liquid refrigerant is conducted for evaporation therein in the presence of inert gas to produce a refrigerating effect, one of said parts being arranged to hold liquid and being connected in said system to cause flow of hot vaporous fluid into said gas circuit when liquid is removed therefrom, and means responsive only to a temperature condition affected by said cooling element to cause removal of liquid from said one part.
15. In a refrigeration system having an inert gas circuit including a place of evaporation subject to formation of frost or ice and in which liquid refrigerant evaporates in the presence of inert gas to produce a refrigerating effect, the improvement which consists in collecting liquid refrigerant at a place of accumulation, removing refrigerant fluid from the place of accumulation to the gas circuit to increase the partial pressure of refrigerant vapor in the place of evaporation to raise its temperature sufficiently to melt frost or ice, and also simultaneously removing refrigerant fluid from the place of accumulation to the place of evaporation for retention therein, whereby such refrigerant fluid is available to produce a refrigerating effect when refrigerant fluid is permitted to collect at the place of accumulation.
16. In a refrigeration system having a place of evaporation subject to formation of frost or ice and in which liquid refrigerant evaporates in the presence of an inert gas in a place of evaporation to produce a refrigerating effect, the improvement which consists in collecting liquid at a place of accumulation, removing liquid from the place of accumulation to effect an increase in the partial pressure of refrigerant vapor in the place of evaporation and cause the temperature of the place of evaporation to rise sufficiently to melt frost or ice formed thereon, heating a heat transfer fluid at a place of heating removed from the place of accumulation, flowing such heat transfer fluid from the place of heating to a region in thermal exchange relation with the place of accumulation whereby heat is transferred to the place of accumulation to cause removal of liquid therefrom, flowing heat transfer fluid from the region back to the place of heating, and controlling transfer of heat by the heat transfer fluid in accordance with changes in a temperature condition affected by the place of evaporation.
17. The improvement as set forth in claim 16 in which the place of heating is associated with a heated part of the refrigeration system.
18. The improvement as set forth in claim 16 in which the heat transfer fluid is vaporized at the place of heating and condensed at the region in thermal exchange relation with the place of accumulation.
19. The improvement set forth in claim 16 in which heat transfer fluid is vaporized at the place of heating and condensed at the region in thermal exchange relation with the place of accumulation, and controlling flow of the heat transfer fluid to regulate the transfer of heat to the place of accumulation from the place of heating.
20. In a refrigeration system having a place of evaporation subject to formation of frost or ice and in which liquid refrigerant evaporates in the presence of an inert gas in a place of evaporation to produce a refrigerating effect, the improvement which consists in collecting liquid at a place of accumulation, removing liquid from the place of accumulation to effect an increase in the partial pressure of refrigerant vapor in the place of evaporation and cause the temperature of the place of evaporation to rise sufficiently to melt frost or ice formed thereon, heating a heat transfer fluid at a place of heating removed from the place of accumulation, flowing such heat transfer fluid from the place of heating to a region in thermal exchange relation with the place of accumulation whereby heat is transferred to the place of accumulation to cause removal of liquid therefrom, flowing heat transfer fluid from the region back to the place of heating, and controlling transfer of heat by the heat transfer fluid.
21. In a refrigeration system having a place of evaporation subject to formation of frost or ice and in which liquid refrigerant evaporates in the presence of an inert gas in a place of evaporation to produce a refrigerating effect, the improvement which consists in collecting liquid at a place of accumulation, removing liquid from the place of accumulation to effect an increase in the partial pressure of refrigerant vapor in the place of evaporation and cause the temperature of the place of evaporation to rise sufficiently to melt frost or ice formed thereon, heating a heat transfer fluid at a place of heating removed from the place of accumulation, flowing such heat transfer fluid from the place of heating to a region in thermal exchange relation with the place of accumulation whereby heat is transferred to the place of accumulation to cause removal of liquid therefrom, flowing heat transfer fluid from the region back to the place of heating, and controlling transfer of heat by the heat transfer fluid.
22. The improvement as set forth in claim 21 in which the place of heating is associated with a heated part of the refrigeration system.
23. The improvement as set forth in claim 21 in which the heat transfer fluid is vaporized at the place of heating and condensed at the region in thermal exchange relation with the place of accumulation, and controlling flow of the heat transfer fluid to regulate the transfer of heat to the place of accumulation from the place of heating.
